MEASURED DOSE DISPENSING CLOSURE FOR
A JAR OR THE LIKE

Emanuel Dee, Nassau, Bahamas, assignor to Dee's
International S.A., Nassau, Bahamas

Filed Nov. 20, 1968, Ser. No. 14,551

Term of patent 14 years

Int. Cl. D9—02

U.S. Cl. D9—275

FIG. 1.

FIG. 2.

FIG. 3.

FIG. 4.

FIG. 5.

FIG. 6.

FIG. 1 is an elevational view of a measured dose dispensing closure for a jar or the like showing my new design;

FIG. 2 is an elevational view looking from the right of FIG. 1;

FIG. 3 is a sectional view taken on the line A—A of FIG. 1;

FIG. 4 is a bottom plan view;

FIG. 5 is a perspective view; and

FIG. 6 is a top plan view.

I claim:

The ornamental design for a measured dose dispensing closure for a jar or the like, substantially as shown.
